CLAIM

The ornamental design for a handbag, as shown and described.

DESCRIPTION

FIG. 1 is a perspective view of my design as it would appear with the top portion not spread apart;

FIG. 2 is an elevation view of one side of my design, the other side being the mirror image thereof;

FIG. 3 is a front elevation view of my the design;

FIG. 4 is a rear elevation view of my design;

FIG. 5 is a top elevation view of my design;

FIG. 6 is a bottom elevation view of my design;

FIG. 7 is a side elevation view of my design as it would appear with the top portion spread apart, the other side being the mirror image thereof; and,

FIG. 8 is a top elevation view my design as it would appear with the top portion spread apart.

In all Figures, the light stippling is intended to indicate a fabric material.

In FIGS. 1-8, the heavily stippled front panel is intended to indicate fur or a fur-like material.
